CONTAINER WITH COVER
Gordon James Thompson, Albuquerque, N. Mex.,
assignor to Push Button Container Corporation,
Albuquerque, N. Mex., a corporation of New
Mexico

Filed Apr. 15, 1963, Ser. No. 272,942
3 Claims. (Cl. 220—60)

Our present invention is directed to containers or boxes having a relatively rigid base and having removable cover means releasably mounted on the base receptacle, and provided with cooperating releasable fastening means on the receptacle and on the cover, and means for manually holding the receptacle during the removal of the cover therefrom.

Presently known two-piece boxes and containers having inter-fitting telescopic portions have certain objectionable features for certain special uses, such as powders, powder-like and granular materials, comminuted and relatively small articles which spill relatively easily when the covers are separated from the receptacle portions thereof. Such present interfitting boxes and covers usually have the side portions frictionally and slidably engaging each other for sealing the contents and in connection with which a lifting or pulling off of the cover usually also lifts the receptacle and contents which frequently drops after being lifted a short distance with the resulting spilling of contents. Such lifting movements of present two-piece inter-fitting boxes necessitate the gripping and holding down of the base container while the user's other hand pulls off the cover, and in many types of telescopic boxes such holding down of the base container is difficult, inconvenient and impossible with consequent spillage of contents.

It is an important object and accomplishment of our invention to provide a container which has a removably and releasably mounted closure and cooperating releasable inter-locking locking means on the closure and on the base of the container respectively and having means removably mounted and retained in the closure or cover which is adapted to be manually depressed with one or more fingers of the same hand of the user which removes the cover or closure from the base portion of the container.

A further object of our invention is to provide a container made of either metal or plastic or of a combination thereof, with cooperating removable closure and sealing means associated therewith, said sealing means being movably mounted within and relative to said closure and being positioned to be accessible for manual contact to maintain the latter in closing sealing engagement with a base container during the manual removal of the main portion of said cover; and which said cover and base receptacle have cooperating releasable locking means thereon adapted to be disengaged and released upon upward manual movement of said cover.

A further object of our invention is the provision of a container having the characteristic recited in the preceding paragraphs and having a plurality of projections, flanges or beads upon the normally inner face of a sealing plate which aid in sealing said plate relative to the upper periphery of the container receptacle; and in which a portion of the sealing plate is normally exposed to manual contact and pressure for the purpose of holding the receptacle and its contents in sealed position during the unlocking, disengaging movements of the cooperating releasable elements mounted on the cover and on the receptacle respectively, so that lifting of the receptacle from its supporting surface may be avoided during the cover removing steps.

It is a further object of this invention to provide a

container which does not rely merely on the continuing frictional engagement characteristic, of ordinary boxes, with covers or the frictional engagement of screw-type closures, and which has cooperating releasable interlocking members upon the receptacle and upon the cover respectively which are adapted to either snap into locking engagement or to separate upon lifting of the cover or closure.

It is a further object of this invention to provide a container of the described class and which can be manufactured inexpensively and in a wide variety of shapes and sizes, and which may be of either plastic, metal or of a combination thereof.

Other and further important objects of the invention will be apparent from the following description and appended claims.

As shown on the drawings:

FIG. 1 is a top plan view of my novel container and removable cover.

FIG. 2 is an enlarged cross-sectional view taken on a plane indicated by line 2—2 of FIG. 1, and showing the cover enclosed in and locked position.

FIG. 3 is an enlarged cross-sectional view taken on a diametrical plane indicated by line 2—2 of FIG. 1, and illustrating the cover member and closure plate in upraised partially removed position with respect to the lower portion of said container.

Referring to the drawings, reference numeral 10 designates a substantially cup-shaped upwardly opening receptacle which may be of varying shapes and sizes and which is preferably formed by molding the same from suitable plastic, though which can be made of metal and other suitable rigid material. The upwardly extending side walls of the receptacle 10 has formed integral therewith an outwardly and downwardly extending annular base flange or skirt member 11 which is of greater circumference than the receptacle 10, and which is slightly yieldable, preferably extending downwardly to a plane a short distance below the bottom of the receptacle 10. Said depending flange 11 has formed integrally therewith an outwardly projecting relatively small annular bead 12 which forms a part of the releasable locking means hereinafter described. The outer annular face of the side walls of said receptacle 10 are preferably inclined inwardly and upwardly as indicated.

Reference numeral 13 generally designates a substantially cup-shaped removable cover or closure member made of either metal or plastic and which has a substantially flat integral upper wall 14 and a central enlarged aperture 15 therein. Said cover or closure member 13 has an integral depending substantially annular skirt 16 which is gradually of reduced thickness towards its lower periphery and which is partially defined by a relatively deeper annular inwardly opening recess 17 which terminates at an annular integral inwardly extending shoulder or bead 18 which is shown in cross-section in FIGS. 2 and 3.

The normally lower reduced portion of the skirt 16 has formed integrally therewith a short distance inward of its periphery a projecting locking means which preferably is an inwardly extending integral bead or flange 19 as illustrated. The circumference of the inner portion of the bead 19 is slightly less than the circumference of the bead 12 so that when said cover is pressed downwardly to closed position, the lower part of said skirt 16 will slightly flex outwardly and bead 19 will frictionally engage and flex inwardly and will slide and snap over the bead 12 so as to be releasably held in closing position by said bead 12.

Reference numeral 20 designates a closure and sealing plate which is preferably formed of rigid plastic or other equivalent material, and which is preferably of substantially annular shape and of a size slightly less than the

inner circumference defined by the annular recess 17, so that said closure plate is seated within and movable within the upper and lower limits of said recess 17. Said closure plate, after being preformed, is pressed into the position between the annular shoulder 18 and the upper wall 14 during which mounting the skirt 15 will slightly flex outwardly to permit said closure plate to snap into position.

Said closure plate 20 has a central upraised boss or head 21 which is preferably grooved and corrugated as illustrated, and which is of a size so that it will extend into and be exposed through the aperture 15 of said cover 13 when said cover is in substantially closed position, as illustrated in FIG. 2.

Said closure and sealing plate 20 also has a pair of integral slightly spaced apart concentric beads 22 and 23 adjacent its periphery and which provide an annular groove as illustrated, which is adapted to engage and rest upon the upper periphery of the receptacle 10 to effectively seal said receptacle.

Said cover 13 preferably has an integral peripheral flange 25 formed thereon which facilitates manual gripping of said cover and prevents the user's fingers from slipping therefrom when said cover is pulled upwardly from locking and closed position. During such removal of the cover, the user will normally grip the cover about its outer portions and place one finger, preferably the forefinger, upon the boss 21 and thereby hold the said closure and sealing plate 20 and the receptacle 10 and its contents against its supporting surface. The upward pulling movement upon said cover will cause the skirt 16 to slight flex outwardly and flange 19 will move upwardly and snap over the annular flange 12, whereupon the receptacle will continue to rest upon its supporting surface during the continued withdrawal of said cover assembly. As said cover is lifted upwardly, the closure and sealing plate 20 will have been moved downwardly to the limit permitted by engagement of the inner annular shoulder 18 which causes the receptacle to remain on its supporting surface and said closure and sealing plate 20 to be retained within said cover and so that the same will be in position for re-sealing of the said closure plate when the cover is again moved into closed locking position.

It will be understood that the normally rigid material from which the depending skirt 16 is formed integrally with the cover 14 is slightly yieldable and sufficiently flexible to permit the normally lower periphery of said skirt 16 to move slightly outward and snap over the lower annular bead 12 when said cover is manually pressed into closed position. When said cover is pulled upward from closed position the peripheral portion of said skirt 16 and the inner beveled bead 19 will snap over the beveled bead 12 during upward movement.

We desire it to be understood that cooperating inter-engaging fastening elements equivalent to the cooperating beads 12 and 19 may be utilized and formed upon the base container and upon the skirt of the cover for releasably retaining said cover in closed position, and which said cover at the same time will hold the sealing plate 20 in sealing engagement with the upper periphery of the receptacle or container 10, as illustrated in FIG. 1.

We further desire it to be understood that our said invention is not limited to rounded or annular shape, but may be of a wide range of varying shapes, depths and dimensions. Further, it is to be understood that the releasable locking means and beads hereinbefore described with reference to the illustrated preferred form of our invention may vary and need not be continuous and may be in spaced-apart relation.

We further desire it to be understood that the shape and size of the upwardly extending middle portion of the

depressable sealing plate 20 may vary in size, shape, and degree of projection. Further, we desire it to be understood that said container or said receptacle and its cooperating cover may be made of suitable materials other than metal or plastic, for example, glass and alloys having substantially equivalent characteristics.

Our said invention provides the novel advantages and characteristics previously pointed out in the objects and accomplishments recited in this specification.

While the foregoing specification sets forth the invention in specific terms, it is to be understood that numerous changes in the shape, size and materials may be resorted to without departing from the spirit and scope of the invention as claimed hereinafter and it is contemplated that various changes may be made in the embodiment of the invention herein specifically described without departing from or sacrificing any of the advantages of the invention or any features thereof, and nothing herein shall be construed as limitations upon the invention, its concept or structural embodiment as to the whole or any part thereof except as defined in the appended claims.

I claim:

1. A container of the character described comprising an upwardly opening receptacle having a depending annular flange and an annular outwardly extending bead integral with said flange, said base including a hollow receptacle open at the top and having securing means on its side; a cover assembly having an integral skirt and having an integral substantially flat upper wall, having a central opening in said upper wall; locking means on said skirt adapted to releasably engage said bead on said flange; said cover having an inwardly extending annular bead below said upper wall; an inner cover plate having a pair of concentric integral annular ridges inward of the periphery of said plate; an upwardly extending boss integral with the middle portion of said upper wall and adapted to extend into the opening of said upper wall, said cover plate being movable between said upper wall and said inner bead on said cover; said concentric ridges being adapted to be positioned on opposite sides of the periphery of said receptacle.
2. A container of the character described comprising an upwardly opening base receptacle, said receptacle having a radially extending projecting member and a depending integral base flange; a cup-like cover having a transversely extending upper wall and a central opening in said wall, said cover having a yieldable skirt portion; inwardly extending locking means on the inner portion of said skirt adapted to releasably engage said projecting member on said receptacle to secure said cover; an inner cover plate; an inwardly extending annular shoulder on said skirt of said cover and spaced from the upper part of said cover and adapted to retain said plate in said cover, said plate being movable between said shoulder and the upper wall of said cover and being partially exposed through said central opening.
3. A container as recited in claim 2 having spaced apart concentric beads integral with the peripheral portion of said plate and defining a groove there-between which is adapted to seat on the periphery of said receptacle.
